(57) **CLAIM**

I claim the ornamental design for a compact steam ironing apparatus, as shown.

DESCRIPTION

FIG. 1 is a left side view of the compact steam ironing apparatus showing my new design;
FIG. 2 is a right side view thereof;
FIG. 3 is a front side view thereof;
FIG. 4 is a rear side view thereof;
FIG. 5 is a top plan view thereof; and,
FIG. 6 is a bottom plan view thereof.
